UNITED STATES PATENT OFFICE.

WALTER G. ARMSTRONG, OF BRIDGEPORT, CONNECTICUT, ASSIGNOR TO THE AMERICAN TUBE AND STAMPING COMPANY, OF BRIDGEPORT, CONNECTICUT, A CORPORATION OF CONNECTICUT.

LIFTING JACK.

Application filed September 23, 1921. Serial No. 502,731.

To all whom it may concern:

Be it known that I, WALTER G. ARMSTRONG, a citizen of the United States, residing at Bridgeport, Connecticut, have invented certain new and useful Improvements in Lifting Jacks, of which I declare the following to be a full, clear, and exact description.

My invention relates to improvements in lifting jacks and has to do, more particularly, with lifting jacks which are adapted to be manufactured of pressed metal.

In my pending application, Serial No. 497,508, filed September 1st, 1921, I have described and claimed a lifting jack of this type and one of the objects of the present invention is to improve upon the construction of that application, so as to provide a jack construction which will lift and support a greater load with safety.

Another object of my invention is to provide an improved pressed metal pawl construction for use in lifting jacks.

Another object of my invention is to provide an improved and simplified construction for reversing the jack, that is, to change the parts from raising to lowering position, and, vice versa.

Further objects, and objects relating to details and economies of operation and construction, will definitely appear from the detailed description to follow. My invention is clearly defined and pointed out in the appended claims. A structure constituting a preferred embodiment of my invention is illustrated in the accompanying drawings, forming a part of this specification, in which:

Fig. 1 is a side elevation of my improved jack, the operating mechanism being shown in dotted lines.

Fig. 2 is a perspective view of one of the pressed metal pawls used in this jack.

Fig. 3 is a sectional view on an enlarged scale through the upper part of the jack, showing the spring set for lowering movement, and

Fig. 4 is a similar sectional view of a modified construction, showing the spring set for raising.

In the drawings, the same reference numerals refer to the same parts throughout the several views.

The form of lifting jack disclosed in my

pending application, above-mentioned, comprises a casing, a rack slidably mounted in the casing, an operating lever pivoted in the casing, and a pair of pressed metal pawls adapted to engage the teeth of the rack. Of these pawls, one, the lifting pawl, is pivoted on the inner end of the operating lever. In the construction of said application, the pressed metal pawls each comprise side walls and a back wall, the latter being slotted and perforated. A spring is provided, the ends of which extend through the perforations in the back walls of the pawls, and the action of the jack is reversed by shifting the center of the spring from one side to the other of a straight line connecting said perforations. When the center of the spring is nearer the rack than the ends of the spring, said ends yieldingly force the pawls into engagement with the rack and the parts are in raising position. When the center of the spring is further from the rack than the ends, said ends tend to withdraw the pawls and the parts are in position for a lowering movement. In said construction, the shifting of the spring is effected by a pivoted reversing lever and a link connecting a central loop of the spring with said reversing lever. The inner end of the operating lever is provided with a cam surface, which engages the back wall of the retaining pawl, and the casing has a cam surface, which engages the back of the lifting pawl. These cam surfaces force the pawls positively into engagement with the rack, at proper points in the stroke of the operating lever. One feature of my present invention consists in substituting for the form of pawl which I have described above, a pressed metal pawl having a front wall and side walls. In order to provide a bearing for the end of the spring, I bend an ear laterally from the rear edge of one of the side walls and perforate this ear. The end of the spring passes through this perforation. I prefer, also, to slot the front wall of the lifting pawl to permit the central part of the spring to work through it. It is not necessary to slot the front wall of the retaining pawl, but I find it desirable, from the manufacturing standpoint, to make both pawls alike so that they are interchangeable.

In this form, the end of the operating lever does not engage the back of the retaining

pawl and I form cam surfaces on the rear edges of the side walls of the retaining pawl, which are engaged by the lower end of the lifting pawl, as it moves down, to force the 5 retaining pawl toward the rack.

Another feature of my invention consists in the manner in which I secure the casing to the base. Laterally-extending feet on the lower end of the casing are 10 rigidly secured to the base and there are also a pair of side plates which are rigidly secured to the sides of the casing and have flanges rigidly secured to the base.

Another feature of my invention consists 15 in a simplified connection between the central part of the spring and the reversing lever. According to this feature, the central part of the spring is formed into a rearwardly-extending shank, which is directly connected, pivotally, to the reversing 20 lever.

In Figs. 1 and 3, I have shown a jack construction embodying my improved pawl and my improved support for the casing. This 25 construction includes the pressed metal casing, 10, which has a longitudinally-extending channel formed therein and the rearwardly-extending portions, 11, forming a housing for the operating mechanism. The 30 lateral flanges, 12, at the lower end of the casing are welded to the base-plate, 13. I provide a pair of side-plates, 14, which are welded to the sides of casing, 10 and which have the feet, 16, welded to the base-plate. 35 These side-plates may be pressed inwardly, at 15, to lie against the portions, 11, of the casing.

The channel-shaped rack, 17, is slidably 40 mounted in the channel of the casing and has a plurality of teeth, 18, struck out from its base. A head, 19, is mounted on the upper end of said rack. A reinforcing collar, 20, is mounted on the upper end of the casing and has a tongue, 21, which extends 45 within the channel of the rack and prevents dust and dirt from entering the interior of the casing.

A retaining pawl is pivoted in the casing 50 on the pin, 22. Since the retaining and lifting pawls are identical, we shall use the same reference numerals in describing them. Each of these pawls comprises the parallel, 55 spaced side walls, 23, connected by a front wall, 24, the latter having a slot, 25, formed centrally therein. Wherever, in this specification and the claims, I refer to the front wall of either pawl, I mean that wall of the pawl which is nearest to the rack. A tongue, 26, is struck laterally from the rear 60 edge of one side wall and forms a sort of bridge extending between the rear edges of the side walls, 23, and keeping them spaced correctly. This ear, 26, is perforated, at 27, to provide a bearing for one end of the 65 spring. Cam surfaces, 28, are formed on

the rear edges of the side walls for a purpose to be described hereinafter.

The operating lever, 29, has its rear end formed into a socket, 30, to receive the handle, 31. This lever is pivoted in the casing 70 on the pin, 32, and the forward end, 33, of the lever, which extends into the casing, carries a pivot pin, 34, on which the lifting pawl is pivoted. The end, 33, of the lever extends between the side walls, 23, of the 75 lifting pawl. The casing has a cam surface, 42, which cooperates with the back of the lifting pawl, as will be set forth more fully hereinafter.

A wire spring, 35, has its free ends extending through the perforations, 27, of the lifting and retaining pawls, respectively, and bearing against the ears, 26, at said points. The spring, 35, is provided with a central loop, 36, which is connected by a 85 link, 37, with the reversing lever, 38. This lever, 38, is U-shaped and has one leg extending into the casing and pivotally connected with the rear end of link, 37, and the other leg extending along the outside of the casing and terminating in the finger grip, 40. The reversing lever is pivoted in the casing on the pin, 39. The outer leg of the reversing lever engages the stop lug, 41, pressed out from the side wall of the portion, 11, of the casing. 95

The construction shown in Fig. 4 is identical with that just described, except for the formation of the spring and its connection with the reversing lever. In this modified construction, the spring, 43, has its central portion bent or twisted to form a rearwardly-extending shank, 44, having an eye, 45, which receives the pin, 46, by which the shank, 44, is pivotally connected to the inner leg of the reversing lever, 38. The free ends of spring, 43, work in the perforations, 27, of the pawls, just as in the form previously described. In this modification, link, 37, is eliminated, thus reducing 105 the number of parts in the jack. 110

From the description of the parts given above, the operation of my improved lifting jack should be readily understood.

In Fig. 1, the parts are shown in the lifting position so that, when the handle, 31, is worked up and down, the rack, 17, will be raised to lift the load engaged by head, 19. In this position, the center of spring, 35, is nearer the rack than the ends, and the ends of the spring, engaging the pawls at the perforations, 27, force the pawls toward the rack. As the handle, 31, is depressed, the lifting pawl is raised carrying the rack with it, while the retaining pawl rides over a tooth of the rack and snaps into engagement with the next lower tooth. When the handle, 31, is raised, the rack is held from dropping by the retaining pawl, while the lifting pawl moves down, riding over a 125 130

tooth of the rack and springing into engagement with the next lower tooth. This operation is repeated at each stroke of the handle. When it is wished to lower the load, the reversing lever, 38, is shifted to the position shown in Fig. 3. This shifts the center of the spring, 35, so that it is further from the rack than the ends of the springs and, consequently, they tend to move the pawls away from the rack. This tendency is ineffective as long as there is a load on the pawl. In Fig. 3, the handle is lowered and the spring 35, has withdrawn the retaining pawl from the rack. As the handle, 31, is raised, the lifting pawl is lowered and the load causes the rack to drop with said pawl. Toward the end of the up-stroke of the handle, the lower end of the lifting pawl engages the cam surfaces, 28, on the back of the retaining pawl and forces the latter into engagement with the rack, so that the downward movement of the rack is halted and the load is shifted from the lifting pawl to the retaining pawl. When this takes place, the spring, 35, withdraws the lifting pawl from engagement with the rack. Now, the handle, 31, is depressed and the lifting pawl, which is clear of the rack, moves upwardly. Toward the end of this movement, the back of the lifting pawl engages the cam surface, 42, of the casing and is forced by it into engagement with the rack so that, as its upward movement continues, it takes the load from the retaining pawl and spring, 35, withdraws the latter from engagement with the rack. This operation is repeated at each stroke of the handle. The operation of the modified construction shown in Fig. 4 is the same.

The improved pawl which I have disclosed is capable of supporting a very heavy load, because the front wall, 24, is almost exactly in line with the line in which the load is transmitted from the tooth of the rack to the pivot of the pawl. This load is applied longitudinally of the front wall and thus the full strength of the metal is utilized. This is true of both the lifting and retaining pawls. The slot, 25, in the case of the lifting pawl, permits the central portion of spring, 35, to work through it. This results in a very compact structure. The ear, 26, not only provides a bearing for the end of spring, 35, but also insures correct spacing of the side walls, 23, so that they cannot move toward each other and bind on the inner end, 33, of the operating lever. The side plates, 14, give a very strong connection between the casing and the base, 13. As I have already indicated, the modified form of spring, 43, results in a simpler construction by eliminating link, 37.

I am aware that the construction described herein may be altered considerably without departing from the spirit of my in-

vention and, hence, I claim my invention broadly as indicated by the appended claims.

Having thus described my invention, what I claim as new and desire to secure by Letters Patent is:—

1. A device of the class described comprising a casing, a lifting rack slidably mounted therein, a lever pivoted in said casing, and a hollow lifting pawl carried by said lever and engaging the teeth of said rack, said pawl having a front wall, side walls and an ear projecting from one side wall toward the other and perforated to receive an actuating spring.

2. A device of the class described comprising a casing, a rack slidably mounted therein, an operating lever pivoted in said casing, a hollow lifting pawl carried by said lever and engaging said rack, a hollow retaining pawl pivoted in the casing and engaging said rack, each of said pawls having a front wall, side walls and a portion projecting from one side wall toward the other and provided with a hole, a spring having its ends extending through said holes, and means for shifting the center of said spring from one side to the other of a straight line connecting said holes.

3. A device of the class described comprising a casing, a rack slidably mounted therein, an operating lever pivoted in said casing, a hollow lifting pawl carried by said lever and engaging said rack, a hollow retaining pawl pivoted in the casing and engaging said rack, each of said pawls having a front wall, side walls and a portion projecting from one side wall toward the other and provided with a hole, a spring provided with a central loop and having its free ends engaging in said holes, and means engaging said central loop for shifting the central portion of said spring.

4. A device of the class described comprising a casing, a rack slidably mounted therein, an operating lever pivoted in the casing, a hollow lifting pawl carried by said lever and engaging the rack, a hollow retaining pawl pivoted in the casing and engaging said rack, each of said pawls having a front wall, side walls and a portion projecting from one side wall toward the other and provided with a hole, a spring having its ends engaging in said holes, and a reversing lever pivoted on the casing and connected to the central portion of the spring.

5. A device of the class described comprising a casing, a rack slidably mounted therein, an operating lever pivoted in the casing, a hollow lifting pawl carried by the lever and engaging said rack, a hollow retaining pawl pivoted in the casing and engaging said rack, each of said pawls having a front wall, side walls and a portion projecting from one side wall toward the other and provided with a hole, the front wall of

the lifting pawl having a slot therein, a spring working in said slot and having its ends engaging in said holes, and a pivoted reversing lever connected to the central portion of said spring.

6. A device of the class described comprising a casing, a rack slidably mounted therein, an operating lever pivoted in the casing, a hollow lifting pawl carried by said lever and engaging said rack, a hollow retaining pawl pivoted in the casing and engaging said rack, each of said pawls having a front wall, side walls and a portion projecting from one side wall and provided with a hole, the front wall of the lifting pawl having a slot therein, a spring having a central loop therein working in said slot and having its ends engaging in said holes, a pivoted reversing lever, and a link connecting said loop and the reversing lever.

7. In a lifting jack, in combination with a casing, a rack and an operating lever, a pressed metal pawl carried by said lever and comprising a front wall, spaced side walls and a portion projecting laterally from the rear edge of one side wall toward the other side wall and provided with a hole.

8. In a lifting jack, in combination with

a casing, a rack and an operating lever, a pressed metal pawl carried by said lever and comprising a front wall, spaced side walls and an ear struck laterally from the rear edge of one side wall and bridging the space between said side walls, said ear being provided with a hole.

9. In a lifting jack, in combination with a casing, a rack, and an operating lever, a pressed metal pawl carried by said lever and comprising a front wall, spaced side walls and an ear extending laterally from the rear edge of one side wall and perforated, said front wall having a central slot therein.

10. In a lifting jack, in combination with a casing, a rack and an operating lever, a channel-shaped, pressed metal pawl carried by said lever with the base of the channel presented toward the rack, said pawl having a perforated ear projecting laterally from the rear edge of one of the side walls thereof toward the other side wall, and a pawl-actuating spring engaging in said perforated ear.

In testimony whereof, I affix my signature.

WALTER G. ARMSTRONG.
